W. W. WILLIAMS

IGNITION DEVICE FOR LIQUID FUEL BURNERS

Filed Dec. 1, 1924

Inventor.
By Walter W. Williams
C. F. F. & F. F. Attorney's.

UNITED STATES PATENT OFFICE.

WALTER W. WILLIAMS, OF BLOOMINGTON, ILLINOIS, ASSIGNOR TO WILLIAMS OIL-O-MATIC HEATING CORPORATION, OF BLOOMINGTON, ILLINOIS, A CORPORATION OF ILLINOIS.

IGNITION DEVICE FOR LIQUID-FUEL BURNERS.

Application filed December 1, 1924. Serial No. 753,167.

My invention relates to liquid fuel burning devices and more particularly to an ignition means therefor.

The object of my invention is in the provision of a combined gas supply control and spark device for igniting a liquid fuel burning device.

Another object of my invention is in the provision of an ignition mechanism for a liquid fuel burning device comprising a mechanically operating means controlled by the action of the burner for operating simultaneously and temporarily a gas supply and jump spark circuit.

15 A still further object of my invention is in the provision of an ignition mechanism for a fuel burning device comprising an auxiliary independent gas supply operatively connected with the fuel burning device, and a spark-20 ing device disposed adjacent the discharge end of the burner, said sparking device being energized temporarily upon the commencement of operation of the burner and acting simultaneously with the gas supply to ignite 25 the discharged fuel mixture.

A further object of my invention is in the provision of a combined gas supply and spark ignition mechanism for liquid fuel burners, wherein the gas supply is intimately associated with the burner device, and mechanism adapted to energize the jump spark circuit upon commencement of operation of the burner and to simultaneously release a determined amount of gas for the purpose of 35 initially igniting the discharged fuel mixture.

A still further object of my invention is in the provision of a means for atomizing a fuel mixture, and an ignition mechanism for igniting said fuel mixture including a combined 40 gas supply and jump spark circuit, said gas supply being connected with the fuel atomizing member and having a valve member therein controlled simultaneously with the action of the jump spark circuit which is adapted to operate temporarily upon the commencement 45 of operation of the burner.

Other objects of my invention will appear in the following specifications taken in connection with the annexed drawings in which

50 Fig. 1 is a vertical view shown partially in section for the purpose of illustrating in detail portions thereof.

Fig. 2 is a plan view of Fig. 1.

Fig. 3 is an enlarged detail of a portion of the ignition control mechanism. 55

Fig. 4 is a detailed showing partially in section of the gas valve.

Fig. 5 is a side elevation of the fuel burning device showing diagrammatically the general electrical connections. 60

Fig. 6 is an enlarged detail of a portion of the fuel burner; and

Fig. 7 is a cross-sectional view of the fuel atomizer.

Referring to the drawings, I have shown, 65 in Fig. 5, a general view of a liquid fuel burning device, the same having been described in detail in applicant's patent bearing No. 1,451,798.

Although described in detail in said patent, 70 it is thought necessary to describe, at least generally, the main elements and operation of the burner.

An electric motor is shown at 10, the axis 11 of said motor forming the power connection for the associated portions now to be described. 75

Mounted in connection with the electric motor and driven by the axis 11 thereof is an atomizing pump 12, said atomizing pump being made up of the following elements: 80

An outer casing is referred to as 13, and a rotor 14 is mounted upon the axis or motor shaft 11 in an eccentric relation to the casing 13. Sliding vanes 15 are located in the rotor 85

14. Fuel inlet means to the atomizing chamber is shown at 16, as well as an air inlet 17 into the fuel pipe. A fan casing 18 is likewise attached to the electric motor, said fan casing housing a fan member (not shown). 90 A draft tube 19 houses the blast from the fan which is delivered to the discharge point 20 of the burner. A fuel mixture discharge tube is shown at 21 leading from the atomizing chamber to the discharge point or nozzle 20 95 of the burner.

The above description of the general elements of the burner have been given for the purpose of generally describing the burner itself, the operation of which is as follows: 100

Fuel and air are induced into the atomizing chamber by the action of the rotor, whereby a complete atomization takes place, and the resultant mixture discharged through the pipe 21 passing through the nozzle 20 and into the combustion chamber (not shown). 105

The present application is directed to ignition mechanism associated directly with the burner itself and includes the following mechanism:

5 As stated in the objects of the invention, this application is directed to a combined gas supply control and spark ignition mechanism, the same being associated with and controlled by the initial action of the burner.

10 Fuel burning devices were originally and, in some instances, even now ignited by a continuously burning gas pilot light. Progress in the field of fuel burning devices for domestic installation has advanced beyond this 15 point and, in many instances, the discharged fuel mixture is ignited now by a spark device.

There are instances where the use of a spark as an ignition means is not successful 20 and this mainly when fuel of a low specific gravity is used.

To insure absolute ignition of the discharged fuel mixture, applicant originally devised a gas supply control wherein a gas 25 pilot was located adjacent the discharge nozzle of the burner and a jump spark was located adjacent thereto in a manner to ignite a determined supply of gas issuing therefrom, temporarily, upon the commencement of operation 30 of the burner. The application describing such mechanism is now pending and bears Serial No. 578,618, being filed July 31, 1922. The present application, although similar in a great many respects to the application 35 above mentioned, nevertheless, has a different and more successful manner of handling the gas supply used for ignition purposes.

Referring to the drawing, in Fig. 2 is described 40 a closed pressure operated mechanism adapted to automatically control a gas supply and jump spark circuit. A tube 22 connects the atomizing chamber with a diaphragm member 23 located in a skeleton housing 24. Any 45 rise in pressure within the atomizing chamber is transmitted directly to the diaphragm member, the upper and lower positions of which may be noted by the dotted lines shown thereon.

50 The upper side of the diaphragm 23 has a lug 25 located thereon and adapted to operate a pivoted lever 26 upon expansion of the diaphragm 23. Skeleton frame 24 supports, at one side, a formal dash pot 25^a, the piston 55 27 of said dash pot being operatively connected with one end of the lever 26. The skeleton frame 24 supports at its opposite side a gas valve made up of the following portions:

60 A gas inletway is shown at 29 and communicates with the chamber 30 wherein is located a valve member 31, said valve member being tensioned by the coil spring 32 and accordingly held upon its seat 33. The valve

stem 34 projects through the upper side of 65 the chamber or housing 30 and is slidable therethrough. The lever 26 is pivoted at 35 in a supporting post 36 attached to the frame 24.

As has been described, the lever 26 has one 70 of its ends operatively connected with the piston 27 of the dash pot. However, the opposite end has a peculiar operative connection with the gas valve, said action being as follows:

A coil spring 37 connects the valve operating end of the lever 26 with the post 36 and normally tends to hold the lever in a raised position with respect to the gas valve. Pivoted to the lever 26 is a valve operating lug 38 fastened in such manner that, upon downward movement of the lever 26 induced by the expansion of the diaphragm 23, it will depress the valve 31 for a determined time and, thereafter, release said valve or rather, the stem 34 thereof and assume the position shown in dotted lines in Fig. 1.

Relative to the operation of the above mechanism, it may be seen that, upon commencement of operation of the burner and, hence, movement of the rotor in the atomizer, a pressure will be built up gradually therein, with the result that a gradual expansion of the diaphragm 23 will directly affect the lever 26 and, hence, raise it against the retarding action of the dash pot 25^a. The upward movement of the lever results in the lowering of the valve operating lug 38 and, hence, depresses, or rather opens, the gas valve temporarily, or better, until the lug 38 moves to 100 the dotted line position shown in Fig. 1 and indicated as 39.

A gas outlet from the chamber 30 is described as 40, said gas outlet leading through the tube 41 to a point 42 between the air inlet 105 and fuel inlet to the atomizing chamber. It may be clearly seen that the action of the rotor within the atomizing chamber induces not only a flow of air and fuel thereinto, but during the temporary opening of the gas valve, also induces a flow of gas thereto.

So far, nothing has been said relative to the sparking mechanism which comprises the following elements:

A spark coil is shown at 43, said coil being 115 connected in any suitable manner in the electrical circuit of the burner. Electrodes 44, in connection with the coil 43, are disposed adjacent the discharge end of the burner and directly in the path of the discharging fuel mixture.

I have described merely a simple jump spark circuit, but it is understood, of course, that any means of producing a spark at the point of discharge could be readily used.

Included in the electrical circuit to the sparking mechanism is electrical connection 125 45 running to a knife switch 46 upon the

frame 24, said knife switch normally receiving the lever 26 when in its lower or inoperative position.

Inasmuch as the present application does 5 not relate to any control mechanism for the burner, other than the ignition mechanism, no attempt has been made to describe the operation other than to say that the burner is automatically controlled by a house thermo- 10 stat and operates through a series of switches.

Upon the commencement of operation of the burner, the electrical circuit to the sparking device is completed and maintained until the lever 26 has been raised sufficiently by 15 the expansion of the diaphragm 23 to lift it out of the knife switch, hence, opening the circuit in the sparking mechanism and, thereby, resulting in a discontinuance of the spark as an ignition element adjacent the discharge 20 end of the burner.

It is obvious that the action of the gas valve and sparking device is simultaneous as well as dependent upon the initial movement of the device for their operation.

25 Perhaps it would be well, at this time, to distinguish the present structure from that of applicant's co-pending application for a gas supply control above mentioned. The former structure resulted in a temporary delivery of gas from an independent supply adjacent the discharge end of the burner. The present structure results, not in the mere opening of a valve and the release of gas temporarily to a point adjacent the discharge 30 end of the burner, but a valve is opened in the auxiliary gas supply and a flow is induced therethrough by the action of the rotor in the atomizing chamber. The advantage of the latter structure may be illustrated by an 35 actual statement of facts, inasmuch as the ignition of the device is dependent upon the flow of gas.

In case the gas pressure is low, a small amount of gas will issue adjacent the discharge end of the burner, that is, of course, with the structure described in the co-pending application. Naturally, the time of opening of the gas valve is limited and, hence, with low gas pressure, an insufficient 45 amount of gas for ignition purposes will issue and, therefore, prevent the ignition of the discharging fuel mixture which would throw into operation the safety controls and, hence, 50 cut out the operation of the burner until 55 service.

With the present structure, no matter what the gas pressure, whether it be high or low, the activity of the rotor induces a flow of gas into the atomizing chamber where it is joined with the fuel mixture and discharged 60 as a part of said mixture. Naturally, the gas loses none of its ignition qualities and is readily ignited by the sparking mechanism upon discharge. The fact that it is temporarily part of the fuel mixture merely expedites the ignition of the latter. 65

The development of the present structure was occasioned directly from instances above described, wherein there was a failure of gas pressure, or a very low pressure, and the disadvantages of the structure described in the above mentioned application were entirely overcome by using the action of the rotor to induce a flow of gas into the atomizing chamber. 70

75 What I claim is:

1. In an electrically-operated liquid fuel burner including a motor for supplying liquid fuel to the burner nozzle, electrically-actuated ignition means adjacent the burner nozzle, an auxiliary gas supply connected to the liquid fuel supply means, means for simultaneously operating the fuel supply motor and ignition means and causing said fuel supply means to deliver the auxiliary gas to the burner nozzle whereupon it is ignited by the ignition means, and means actuated by the accumulated pressure created within the fuel supply means after initial operation to cut off the auxiliary gas supply and discontinue the operation of the ignition means. 80

2. In an electrically-operated liquid fuel burner including a motor for supplying atomized liquid fuel to the burner nozzle and additional air thereabout, an electrically-actuated ignition means adjacent the burner nozzle, an auxiliary gas supply connected to the liquid fuel atomizing means, means for simultaneously operating the fuel supply motor and ignition means, whereby the auxiliary gas and atomized fuel issuing from the nozzle are ignited, and means actuated by the accumulated pressure created within the liquid fuel atomizing means after initial operation to cut off the auxiliary gas supply and discontinue the operation of the ignition means. 85 90 95 100 105

In testimony whereof, I have affixed my signature.

WALTER W. WILLIAMS.
